Patented Dec. 5, 1916.

UNITED STATES PATENT OFFICE.

GEORGE D. POGUE, OF ST. LOUIS, MISSOURI.

FUEL-PUMP.

1,207,324.

Specification of Letters Patent. Patented Dec. 5, 1916.

Application filed December 21, 1915. Serial No. 68,035.

To all whom it may concern:

Be it known that I, GEORGE D. POGUE, a citizen of the United States, residing at St. Louis, Missouri, have invented a certain new and useful Improvement in Fuel-Pumps, of which the following is a full, clear, and exact description, such as will enable others skilled in the art to which it appertains to make and use the same.

10 This invention relates to pumps, and particularly to pumps of the type that are used for supplying liquid fuel to the cylinders of oil engines.

15 The main object of my present invention is to provide a fuel pump which is so constructed that it can be repaired quickly, in case the valves of the pump become defective or inoperative. To this end I have devised a pump in which the inlet and discharge valves are carried by a member separate and distinct from the cylinder of the pump that can be removed and replaced easily by a similar valve-carrying member whenever the valves get out of order. In a 20 multi-cylinder pump the inlet and discharge valves of the respective cylinders are carried by separate valve units or members, each of which can be removed or disconnected from its coöperating cylinder without disturbing 25 the other valve units or affecting the operation of the remaining cylinders of the pump.

30 Figure 1 of the drawings is a vertical sectional view of a multi-cylinder fuel pump constructed in accordance with my invention. Fig. 2 is a front elevational view of same. Fig. 3 is a horizontal sectional view, taken on the line 3—3 of Fig. 2. Fig. 4 is a detail sectional view, illustrating the elastic gasket that is arranged between each 35 valve unit and the body portion of the pump; and Fig. 5 is a perspective view of the cylinder casting or body portion of the pump in which the cylinders are formed.

35 Referring to the drawings, which illustrate the preferred form of my invention, A designates the cylinder casting or body portion of the pump in which the cylinders 1 are formed, the pump herein illustrated being provided with three cylinders. Each 40 cylinder is provided with an inlet valve 2 and with one or more discharge valves 3, and the valves of the respective cylinders are carried by separate and distinct valve-carrying members or valve units B that are 45 detachably connected to the body portion A of the pump. It is immaterial, so far as my

broad idea is concerned, how the removable valve units B are constructed, or how they are combined with the portion of the pump in which the cylinders are formed. It is 60 also immaterial whether the pump is provided with a single cylinder or a plurality of cylinders, for my broad idea consists in a pump having a cylinder, suitable valves of any preferred type for governing the inlet 65 and discharge of the medium being pumped into and out of the cylinder and a removable member that carries said valves and which is adapted to be removed whenever the valves become defective or inoperative and a similar member equipped with perfect valves substituted therefor.

70 In the form of my invention herein illustrated each of the removable valve units B is composed of a casing 4, preferably of cylindrical shape, an inlet valve 2 and one or more discharge valves 3 arranged inside of said casing and removable cages or seats 2^a and 3^a in said casing for said inlet and discharge valves, respectively. The seat 2^a 75 for the inlet valve rests on a shoulder 5 formed on the casing 4, and said valve seat is provided with a tubular portion 2^b that projects downwardly through a hole in the lower end portion of the casing 4, as shown 80 in Fig. 1, the lower end of said hole being closed by a solid, externally screw-threaded plug 2^c on which a nut 6 is mounted in such a manner that it bears against the lower end of the casing 4. Consequently, whenever the nut 6 is tightened, the valve seat 2^a 85 will be drawn tightly into engagement with the shoulder 5 on which it rests. The valve seat 3^a for the bottom discharge valve 3 rests on a shoulder 7 on the inside of the casing 4, but the seat 3^a for the upper discharge valve is mounted directly upon the upper edge of the seat 3^a for the bottom discharge valve, as shown in Fig. 1. A stop member 8 90 that limits the upward movement of the upper discharge valve rests upon the upper edge of the seat 3^a for said valve, and means is provided for exerting downward pressure 95 on said stop member 8 and on the two valve seats 3^a arranged underneath same, so as to clamp the lower valve seat 3^a tightly against the shoulder 7 in the casing, the means herein illustrated for this purpose consisting of a plug 9 that is screwed into the upper end 100 of the casing 4 at a point directly above the stop member 8. If desired, a removable cap 105 nut 10 can be mounted on the plug 9, so as

to seal the threads between said plug and the casing 4, and thus form an absolutely tight joint, said cap bearing upon the upper edge of the casing 4.

- 5 In the pump herein shown the cylinder casting A is provided with a supply manifold 11 from which the supply for all of the cylinders 1 is drawn. Separate discharge ducts 12 are formed in the cylinder casting, 10 for the respective cylinders, however, and each cylinder 1 is provided in its side with a combined inlet and discharge orifice 13 through which the medium being pumped is drawn into the cylinder and discharged 15 therefrom. The removable valve units B are arranged at the front side of the cylinder casting A and the casing 4 of each of said valve units is provided at its rear side with three ports 11^a, 12^a and 13^a that co- 20 operate, respectively, with an opening 11^b in the supply manifold and with the discharge duct 12 and the combined inlet and discharge orifice 13 of the cylinder with which said valve unit co-operates. Gaskets 25 are arranged between the removable valve units B and the cylinder casting A at the points where the co-operating ports or openings in said members are formed, and means is provided for securely clamping said valve 30 units to the cylinder casting. Any suitable means may be used to retain the valve units in operative position, but I prefer to provide the cylinder casting with a forwardly-projecting yoke 14 that has three holes or openings 15 for receiving the valve units B, said openings 15 being so proportioned that the sides of each opening bear snugly against the opposite side faces of the valve unit B arranged inside of same. The openings 15 35 are a trifle longer than the external diameter of the casings 4 of the valve units, and the yoke-shaped portion 14 on the cylinder casting is made thick enough to overcome any tendency for the valve units to twist or 40 turn out of vertical alignment with each other, thus insuring proper alignment of the co-operating ports in the valve units and in the cylinder casting. The valve units B are forced rearwardly toward the cylinder 45 casting A by means of set screws 16 or other suitable devices that are mounted in screw-threaded openings 16^a in the cross piece of the yoke 14 on the cylinder casting. The yoke portion 14 is preferably so arranged 50 that each of the adjustable clamping devices 16 in same will exert pressure on its co-operating valve unit B at a point intermediate the ports 12^a and 13^a in the rear side of said valve unit, thus permitting two metal 55 gaskets 17 of the same thickness to be used for packing the joints around the ports 12, 12^a and 13, 13^a. An elastic gasket 18 that is thicker than the gasket 17 and which is formed from leather or some other suitable 60 material that has more or less resiliency, is 65

arranged between the cylinder casting A and each of the valve units B, so as to pack the joints around the ports 11^a in said units and the ports 11^b in the cylinder casting, said gaskets 18 having sufficient resiliency to insure tight joints around the ports referred to, notwithstanding the fact that the clamping devices 16 which retain the valve units in position are arranged some distance above the gaskets 18. In other words, 70 the valve units are clamped to the cylinder casting in such a manner that two of the gaskets of each unit will be subjected to the same clamping pressure, and the third gasket of each valve unit is of such a character 75 that it will be sure to form a tight joint if the joints of the other two gaskets are tight. The cylinder casting and the casings 4 of the valve units are preferably provided with recesses or depressions for receiving the 80 gaskets 17 and 18, as shown clearly in Fig. 1. The tubular-shaped portion 2^b of the valve seat 2^a is provided at its lower end with slots or openings, as shown in Fig. 1, so as to permit the medium being pumped to 85 pass into said tubular-shaped portion, and the stop member 8 that is arranged above the upper discharge valve is provided with a port or opening through which the medium passes in escaping from the casing of 90 the valve unit into the discharge duct 12 in the cylinder casting.

In order that the valve unit of one cylinder may be removed without stopping the pump or affecting the operation of the other 100 cylinders, I have provided the pump with three separate and distinct manually-operable valves 19 for closing the openings 11^b leading from the supply manifold 11 to the inlet ports 11^a of the valve units. As shown 105 in Fig. 1, each of the valves 19 is carried by a stem 20 which is adjustably mounted in a horizontally-disposed guide 21 that is screwed into the rear side of the cylinder casting A at a point in alignment with the 110 supply manifold 11, each of said valves being capable of being moved forwardly so that it will close the opening 11^b in the front wall of the manifold 11, through which the medium being pumped is drawn into the 115 casing of its co-operating valve unit. Normally, the valves 19 are arranged in the position shown in Fig. 1, but whenever it is desired to remove one of the valve units B, the valve 19 that co-operates with said unit 120 is forced forwardly, by turning the stem 20, so as to close the opening 11^b and prevent the contents of the manifold 11 from escaping when the valve unit is removed.

A pump of the construction above described greatly improves the efficiency of an oil engine that is used for driving an electric generator that supplies current for lighting or power or an oil engine that is used in a municipal water works plant, owing to the 125 130

fact that the valves of the respective cylinders are carried by separate removable valve-carrying members. In case the valves of one cylinder become defective or inoperative, the valve unit of said cylinder can be removed easily and another valve unit equipped with perfect valves can be substituted therefor.

It is not necessary to disconnect any pipes 10 in the operation of removing any of the valve units, for the pump is so designed that the removal of a valve unit and the substitution of a valve unit provided with perfect valves can be effected by simply loosening a 15 set screw, slipping the worn valve unit out of its yoke, replacing it with a perfect valve unit and thereafter tightening the set screw. If the pump is a multi-cylinder pump, as herein illustrated, the valve unit of one cylinder 20 can be removed and another valve unit substituted therefor without stopping the pump or affecting the operation of the remaining cylinders.

In addition to the desirable features above 25 mentioned, a fuel pump of the construction herein described can be manufactured cheaply, owing to the fact that all of the valves of a cylinder are carried by a removable member that is separate and distinct 30 from the cylinder or from the casting in which the cylinder is formed.

Having thus described my invention, what I claim, and desire to secure by Letters Patent, is:

35 1. A pump, comprising a member in which a cylinder is formed, said member having a supply duct and a discharge duct, a port in one side of said cylinder, a removable valve unit combined with said member and provided at one side with ports that register 40 with the ducts in said member and with the port in said cylinder, and gaskets arranged between said valve units and said member, one of said gaskets being formed of material 45 that has a greater degree of resiliency than the material from which the other gaskets are formed.

2. A pump, comprising a cylinder and a removable valve unit equipped with valves 50 that govern the admission and discharge of the medium into and out of said cylinder, and a means for closing the passageway through which the medium being pumped is supplied whenever said valve unit is re- 55 moved.

3. A pump, comprising a cylinder provided with a port, a removable valve unit provided with inlet and discharge valves arranged on opposite sides of said port, a supply 60 passageway leading to said valve unit, and a valve that is adapted to be actuated to close said passageway when said valve unit is removed.

4. A pump, comprising a member in 65 which a cylinder is formed, said member

having a discharge duct and a supply passageway, a removable valve unit equipped with inlet and discharge valves and provided on one side with ports that register with the ports in said cylinder and with the discharge duct and supply passageway in said member, and means for preventing the medium being pumped from escaping from the supply passageway in said member when said valve unit is removed.

5. A pump, comprising a member in which a cylinder is formed, a removable valve unit arranged at one side of said member, a portion on said member that receives said valve unit, and an adjustable device in said portion for clamping said valve unit in position.

6. A pump, comprising a body portion and a removable valve unit provided with registering ports or openings that are spaced some distance apart, and a retaining means for said valve unit that exerts pressure on same at a point intermediate said ports.

7. A pump, comprising a member in which a cylinder is formed, a removable valve unit 90 equipped with inlet and discharge valves, a supporting means for said valve unit comprising a portion on said member through which said valve unit can be slipped, and an adjustable device for retaining said valve 95 unit in position.

8. A pump, comprising a member in which a cylinder is formed, a removable valve unit arranged at one side of said member and provided with inlet and discharge valves that are arranged in axial alignment with each other and parallel to the longitudinal axis of the cylinder, a supply port and a discharge port arranged adjacent the opposite ends of said valve unit, 100 and a suction manifold in said member with which said supply port communicates.

9. A pump, comprising a member in which a cylinder is formed, said member being provided with a supply passageway and a discharge passageway, a port in one side of said cylinder, a removable valve-carrying unit arranged at one side of said member and provided with ports that register with the passageways in said member and the port in said cylinder, a yoke-shaped portion on said member that embraces said valve unit, and means for clamping said valve unit tightly against said member.

10. A pump, comprising a member in 120 which a cylinder is formed, said member being provided with a supply passageway and a discharge passageway, a port in one side of said cylinder, a removable valve-carrying unit arranged at one side of said member and provided with ports that register with the passageways in said member and the port in said cylinder, a yoke-shaped portion on said member that embraces said valve unit, an adjustable clamping device on said 125 130

yoke that exerts pressure on said valve unit at a point intermediate two of the ports therein, and gaskets interposed between said member and valve unit, one of said gaskets being formed from material that has more or less resiliency.

11. A multi-cylinder pump, comprising a member provided with a plurality of cylinders, a supply manifold in said member common to all of said cylinders, and removable valve units for said cylinders combined with said member and each being equipped with inlet and discharge valves for controlling the admission and discharge 15 of the medium into and out of the particular cylinder with which said unit co-operates, each of said valve units having an admission port that communicates with the supply port in said member.
12. A pump, comprising a member provided with a plurality of cylinders, and having a supply manifold, removable valve units for the respective cylinders equipped with suitable inlet and discharge valves, and means whereby any of said valve units can be removed without affecting the operation of the remaining valve units or permitting the medium being pumped to escape from the manifold.
13. A pump, comprising a member provided with a plurality of cylinders, a supply manifold in said member, removable valve units for the respective cylinders equipped with suitable inlet and discharge 35 valves, each of said valve units having a port that registers with a discharge opening in said manifold, and independent, manu-

ally-operable valves for closing the discharge openings in said supply manifold.

14. A removable valve unit for pumps 40 consisting of a casing provided with an end wall, a valve seat in said casing provided with a tubular portion that has a solid extension which projects through an opening in said end wall, a shoulder inside of said casing on which said valve seat rests, an adjustable device arranged outside of the end wall of said casing on the solid extension of the valve seat that projects through said opening for clamping the valve seat in position, and a port in the side of said casing that communicates with the interior of the tubular portion of said valve seat.

15. A removable valve unit for pumps, comprising a cylindrical-shaped casing provided on its inside with shoulders, valve seats arranged on the inside of said casing in longitudinal alinement with each other, one of said valve seats having a portion that projects through an opening in the end wall 60 of the casing, means arranged outside of said end wall and co-operating with said portion for clamping one of the valve seats against one of said shoulders, and means arranged at the other end of the casing for 65 clamping the remaining valve seats together.

In testimony whereof I hereunto affix my signature in the presence of two witnesses, this fifteenth day of December 1915.
